UNITED STATES PATENT OFFICE.

ARTHUR J. FREEMAN, OF ALAMEDA, CALIFORNIA, ASSIGNOR TO OTTO ADAMS, OF SAN FRANCISCO, CALIFORNIA.

SIGN-EXHIBITING MACHINE.

1,329,705.

Specification of Letters Patent.

Patented Feb. 3, 1920.

Application filed April 3, 1919. Serial No. 237,340.

To all whom it may concern:

Be it known that I, ARTHUR J. FREEMAN, a citizen of the United States, residing at Alameda, in the county of Alameda and State of California, have invented certain new and useful Improvements in Sign-Exhibiting Machines, of which the following is a specification.

This invention relates to sign exhibiting machines and particularly to the type of device which comprises a housing in which are a plurality of indicating cards that are successively displayed through an opening in the housing.

One of the principal objects of my invention is to provide a machine of this character in which both sides of the cards are exposed to view and in this manner to reduce the number of cards required and so the size of machine, or to give double the number of displays for a given size machine. A further object is to provide a simple and effective mechanism for moving the cards into position and to provide a simple electric contact mechanism by which other devices may be synchronously operated with the displays on the individual cards. I also provide a novel form of card carrier in which two cards are held back to back and which enables them to be quickly changed.

With these and other objects in view my invention consists of certain novel features of construction, combinations and arrangements of parts, hereinafter described and more specifically pointed out in the appended claims.

Reference being had to the accompanying drawings forming a part of the specification:

Figure 1 is a view in perspective showing my improved sign exhibitor.

Fig. 2 is a view in end elevation with the cover shown in section.

Fig. 3 is a view partly in rear elevation and partly in section.

Fig. 4 is a view in section on the line 4-4, Fig. 3.

Fig. 5 is a view in section on the line 5-5, Fig. 3.

Fig. 6 is a fragmentary perspective view of one corner of a card carrier and the means by which they are moved.

Fig. 7 is an enlarged view in cross section through one edge of the card carrier. 55

Fig. 8 is an enlarged sectional view on the line 8-8, Fig. 3.

Referring to corresponding parts in the several views by the same numerals of reference, 1 denotes in general a housing having 60 the supporting members 2 and a frame 3 mounted thereon. The frame is provided with a display opening 4 and the top is inclined to the rear.

Extending between the members 2 is a 65 floor board 5 to which are attached blocks 6. Above each of these blocks is a flat rectangular plate 7, which is set slightly back of the outer side face of the corresponding block 6. These plates are spaced from 70 the rear surface of the frame 3 and from the upper surface of the blocks 6 to form slots 13 and 9 respectively. The plates are attached to the blocks by means of brackets 8 which are recessed opposite the slots 9 75 to permit the passage of certain parts of the card carriers. A plate 10, semi-circular around its upper edge, is attached to the upper end of plate 7, by means of brackets 11 which are similar to brackets 8. This 80 construction forms a slot 12 which is parallel to slot 9. A similar slot 14 is formed at the rear of plate 7 by the strip 15, and this strip is continued in a semi-circle concentric to the upper end of plate 10, thereby forming a slot 16 which connects slots 13 and 14. 85

The signs comprise cards which may be printed on both sides, or may be made up of two cards, each printed on one side and placed in the carriers with their unprinted 90 sides back to back. These cards are held in a carrier 18', which comprises U-shaped parallel clips 18, in the bottom of which are rods 19. The latter project from the ends of the clip and have revolvably mounted 95 grooved rollers 20. The clips are connected to each other by flexible strips 21, which are attached to the rods and are centrally located in the clips. When in position, the cards have their top and bottom edges held in the 100 clips 18, and their side edges attached to the strips 21 by means such as fasteners 21'.

The mechanism for moving the card carriers consists of the endless chains 22, spaced outside of the plates 7, and provided on the 105 sides adjacent thereto with carrier lugs 23.

2

Each of these lugs comprises two parallel arms 24, from the upper of which extends an inclined guide 25. A second set of lugs 26, spaced approximately half way around the chain, is provided for the purpose of operating certain mechanism hereinafter described. Chain 22 is supported in the upper part of the housing by idler wheels 30, which are concentrically mounted with respect to the slot 13. That part of the chain adjacent the frame 3 is parallel to the slot 13, while that portion at the rear of the housing is inclined rearwardly with respect to the bottom of the slot 14.

15 Revolubly mounted in the blocks 6, is a shaft 31 to which is attached toothed sprocket wheels 32, and which drive the chains 22. At the bottom of the rear strand of chain is a small spring depressed idler wheel 33, about which the chain passes and which maintains a uniform tension on the same. Shaft 31 is driven by means of a threaded worm 35 engaging the toothed worm wheel 36. The worm is mounted on 20 the same shaft which carries the grooved pulley 38, which in turn is driven by belt 41 from motor 40. On the shaft 31 is also mounted an electric circuit make and break device, by which the lamp 49 on the face of 25 the frame is constantly flashed.

On the inside of the plates 10 are revolubly mounted a plurality of rollers 42, the outer edges of which are substantially tangential to the edge of the plate. These 30 rollers serve to support the edge of the card carriers as they move around the top of the machine.

Oscillatively mounted on the shafts which carry the wheels 30 are spring depressed 35 arms 43 and 44. The former extends toward the front of the machine and has formed thereon, a hook 45, the forward edge of which is inclined rearwardly. The under edges of these arms rest on the projecting ends of the rods 19, and one of these rods contacting with the inclined face of hook 45, lifts the arm to enable the rod to move thereunder. The other arm is also provided with a hook 47, the inner edge of 40 which is inclined in the same direction as the outer edge of arm 43. This enables the carriers to lift the arm and move from thereunder, while the tension of the spring on the arm is sufficient to prevent movement of the 45 carriers at the wrong time.

The carriers are moved in slot 12 by means of pivotally mounted bell-crank that have arms 51, the lower ends of which are positioned between the rollers 20 and the arms 43, and rear edges of which engage the rod 19. The other arm 52 of each bell-crank is engaged by the forked end of the spring retracted lever 53. This lever is in turn pivotally mounted as at 54, and is operated by 55 one of the lugs 26. Spaced outside of plates

10 are arcuate guides 50, the function of which is to support the under side of the lugs 26, when the latter contact with the lever 53, and thus prevent a twisting strain on the chain.

Attached to strip 15, directly opposite the slots 9 and 13, are small plates 55 which are in the same plane as plates 7 and 10. These guides serve to engage the rollers 20, as they leave contact with plate 7 and thus prevent any end movement of the carriers. This loss of contact is due to the fact that for practical reasons the corners of the plate are slightly rounded and only occurs at these corners. Opposite each slot 12 there is also 80 provided an angle guide 56, which is positioned close to the side and back of the chain 22 and makes certain that the chain remains in contact with the idler 30.

At the bottom of slot 13 the corner of 85 plate 7 is well rounded off as shown at 57, and in the corner between slots 13 and 9, there is an angular block 58, having a width equal to the rollers 20 and disposed in the path thereof. In operation, this block 90 engages the rollers as they are moved down by the clips 23 and causes them to move laterally until the rod is disengaged from the clip.

Below the bottom of the pack of card carriers is a narrow piece of non-conducting material 60, on which are mounted contact strips 61, one for each sign, or two for each carrier. These contacts are arranged in alignment with the carriers and spaced 100 slightly below the bottom edge thereof. Each clip is provided with an outwardly extending lug 62 and the lugs on the various clips are spaced longitudinally so that one lug only will contact with a given strip 61. 105 Each strip is connected by a wire to other devices, which may thus be operated synchronously with the various signs.

The operation is as follows: Chains 22 are continuously driven by sprockets 32 in the 110 direction of the arrow in Fig. 2. One of the card carriers is positioned with the flanges of the wheels resting on the strip 15 and the grooves thereof engaging the pieces 55. Then when the clips 23 move upwardly, 115 the guides 25 contact with the extended ends of the upper rod 19, and cause a lateral displacement of the rod and chain, so that the upper arms 24 are enabled to pass the ends of the rod. Immediately thereafter the 120 parts slip back into position and the rod ends are engaged by the second arms 24, and carried along with the chain. The carrier is in this manner moved in a semi-circle around the upper part on the machine, with 125 the rollers contacting with inner surface of piece 16, and the grooves thereof engaging the edge of plate 10. The rod thus engaged is carried around slot 16 and down slot 13, until the roller strikes block 58. This causes 130

a lateral displacement of the roller into slot 9 and disengages the rod from the lug 23.

In the meantime the lower edge of the carrier has moved through slots 14 and 16, 5 until it is positioned opposite slot 12. In moving around slot 16, the rod ends contact with the lower arm 51 of the bell-cranks and push them forwardly, which in turn moves the levers 53 into the path of the lugs 10 26. As the latter move around, they contact with the under surface of the levers, and raise the latter. This in turn oscillates the bell-cranks, and arm 51 of the latter and forces back the carrier into slot 12. As the 15 carrier moves back the rod ends contact with the inclined face of arm 43, raising this arm to allow the rod to slip thereunder. As the rollers are in contact in the slot 12, this forces the rearmost one from under arm 44 20 and allows it to drop into position in slot 14. Here it is held until it is picked up by the lug 23 in the manner already described.

It will be noted that at the bottom of slot 25 14, the chain is positioned a sufficient distance back, that the lugs 23 do not engage the rod ends at this point. The weight of the carriers is carried on the block 6 and on the upper edge of the plate 7, and it is to 30 cause the rollers to move along these members that the frame is inclined rearwardly. The metal work of the machine is grounded, and the strips 61 are connected to the other side of an electric circuit. Hence whenever 35 a card carrier moves into the rearmost position, the lug on its lower clip engages the corresponding strip 61 and completes an electric circuit to auxiliary devices.

Having thus described my invention, I 40 claim as new and wish to cover by Letters Patent:—

1. An apparatus of the character described, a housing having a display opening therein, a pack of card carriers held in an 45 inclined position back of said opening, rectangular guide plates at the sides of said opening, semi-circular plates positioned above the aforesaid plates, grooved rollers on said carriers for coöperation with the 50 edges of said plates, means for moving said carriers around said semi-circular plate from the back of said rectangular plate to the front thereof, and means for holding said pack while a carrier is being moved as 55 aforesaid.

2. An apparatus of the character described comprising a housing having a display opening therein, guide plates back of said opening, a pack of card carriers 60 normally positioned between said plates, grooved rollers on said carriers for coöperation with the edges of said plates, means for moving said carriers from the rear of said pack to the front thereof, spring depressed front and rear arms for holding 65

the end carriers of said pack, and means for moving said carriers laterally for engagement under the front of said arms and disengagement under the rear of said arms.

3. An apparatus of the character described comprising a housing having a display opening therein, a plurality of card carriers back of said opening, guide plates on the sides of said opening, grooved rollers on said carriers for coöperation with the 70 edges of said plates, chains movable in paths substantially parallel to the outer edges of said plates, and lugs on said chain for engagement with said carriers to successively move the same into position back of 75 said opening.

4. An apparatus of the character described, comprising a housing having a display opening therein, a plurality of card carriers back of said opening, grooved 80 rollers on the edges of said carriers, guide plates forming trackways for said rollers, endless chains movable in paths substantially parallel to the outer edges of said plates, means carried by said chain for engaging said carriers, and means for disengaging the aforesaid means when the engaged carrier is positioned back of 85 said opening.

5. An apparatus of the character described, comprising a housing having a display opening therein, a pack of card carriers back of said opening, rods extending across the top and bottom edges of said carriers, grooved rollers pivotally mounted 90 on said rods, guide plates forming trackways for said rollers, endless chains movable in paths substantially parallel to the outer edges of said plates, lugs on said chains for engaging the said rod on the 95 rearmost of said carriers, and means for disengaging said lug therefrom when said carrier has been positioned in front of said pack.

6. A machine of the character described, 100 comprising a casing, a pack of card carriers adapted to be successively positioned back of said opening, grooved rollers carried by said card carriers, trackways for said rollers, endless chains movable substantially 105 parallel to said trackway, lugs on said chains for moving said carriers, means for holding said pack while a carrier is being moved, means for displacing said pack laterally, and lugs carried by said chains for 110 operating said displacing means.

7. An apparatus of the character described, comprising a pack of card carriers, 115 grooved rollers revolvably mounted on the corners thereof, guideway for said rollers, means for moving said carriers, one at a time from the back of said pack to the front thereof, spring depressed arms engaging the end carriers of said pack, means operable by said carriers moving means forcing the 120 130

last moved carrier under said holding means and rearmost carrier into the path of said carrier moving means.

8. An apparatus of the character described, comprising a housing having a display opening therein, rectangular guide plates positioned back of said opening and having their upper ends downwardly inclined toward the rear of said housing, semi-circular guide plates in the same plane as the plates aforesaid and spaced therefrom, a pack of card carriers normally held between said rectangular plates, said carriers having grooved rollers adapted to engage 15 the edges of said guide plates, endless chains movable substantially parallel to the outer edges of said plates, lugs on said chains adapted to engage said carrier and move the same from the rear of said pack 20 to the front thereof, and means for disengaging said lugs when said carrier is positioned back of said opening.

9. An apparatus of the character described, comprising a housing having a display opening therein, rectangular guide plates back of said opening having their upper ends downwardly inclined toward the rear of said housing, semi-circular guide plates in the planes of the plates aforesaid 25 and spaced apart therefrom, a pack of card carriers normally positioned between said rectangular plates, grooved rollers on said carriers adapted to engage the edges of said guide plates, endless chains on the outside

of said plates and movable substantially 35 parallel to the outer edges thereof, lugs on said chain adapted to engage and move said carriers, means for disengaging said carriers at a predetermined point, and means for holding said carriers while one is being 40 moved as aforesaid.

10. An apparatus of the character described, comprising a housing having a display opening therein, rectangular guide plates back of said opening having their upper ends downwardly inclined toward the rear, semi-circular guide plates in the plane of the plates aforesaid and spaced apart therefrom, a pack of card carriers positioned between said rectangular plates, grooved 50 rollers on said carriers for coöperation with the edges of said plates and normally engaging the top and bottom edges of said rectangular plates, endless chains on the outside of said plates and movable substantially 55 parallel to the edges thereof, lugs on said chains adapted to engage said carriers and move them from the rear of the pack to the front thereof, means for pushing said carrier laterally to disengage from said lug 60 when said carrier is positioned behind said opening, spring depressed arms for holding said pack, means for moving said pack laterally along the top of said rectangular plate, and lugs carried by said chains for 65 moving said last mentioned means.

In testimony whereof I affix my signature
ARTHUR J. FREEMAN.
